UNITED STATES PATENT OFFICE.

FRANK ALLEN, OF MEMPHIS, TENNESSEE.

WINDOW-SASH HOLDER.

SPECIFICATION forming part of Letters Patent No. 638,617, dated December 5, 1899.

Application filed August 10, 1899. Serial No. 726,816. (No model.)

To all whom it may concern:

Be it known that I, FRANK ALLEN, a citizen of the United States, residing at Memphis, in the county of Shelby and State of Tennessee, 5 have invented certain new and useful Improvements in Window-Sash Holders; and I do hereby declare the following to be a full, clear, and exact description of the invention, such as will enable others skilled in the art to 10 which it appertains to make and use the same.

My invention relates to improvements in sash-holders; and it consists in the novel device hereinafter described and claimed.

My invention will be understood by reference to the accompanying drawings, wherein the same parts are indicated by the same letters throughout the several views.

Figure 1 represents a perspective view of the sash provided with my improved holder, 20 parts being broken away for better illustration of the same. Fig. 2 is an enlarged view showing an edge elevation of the window-sash provided with my improved holder. Fig. 3 is a sectional view taken on the line 3-3 in Fig. 25 1. Fig. 4 is an enlarged detail perspective view of the frame which carries the roller of the adjustable sash-holder. Fig. 5 is a perspective view of the compressible roller, and Fig. 6 is a perspective view of the slotted face- 30 plate seen in Fig. 2.

A represents the sash of the window.

B represents the window-frame, provided with usual strips C and C', between which the sash moves freely. At a suitable point on 35 the sash, which is cut away, as at A' in Fig. 3, is mounted the frame D of the holder. This frame D consists of a flat plate so bent as to have a longer member D' and a shorter member D², connected by a portion D³ substantially at right angles to the portions D' and D². The portion D³ is provided with a slot there- 40 through, through which passes the roller-spindle d⁴, the length of the slot allowing the spindle considerable adjustment therein.

The spindle d⁴ has an enlarged rear end d⁵ 45 with a screw-threaded opening therethrough for the passage of a screw D⁴, as seen in Figs. 3 and 4. This screw passes through the members D' and D², having its head upon the outer 50 side of the member D', which coincides with the face of the sash, and the said screw has a smooth boss d⁶ thereon, which may turn freely

in the said member D'. The point of the screw d⁷ is retained within a smooth opening in the member D² by having a smooth portion 55 in the region of its point, which latter is upset or riveted upon the member D². It will thus be seen that the screw D⁴ may be turned freely within the openings through the members D' and D² without any longitudinal motion of the said screw; but by reason of its screw-threaded engagement with the opening 60 through the enlarged base d⁵ of the spindle d⁴ the turning of the screw will have the effect of causing the said spindle to move longitudinally of the screw, this movement being limited only by the distance between the members D' and D² and the length of the slot d³ in the member D³.

The longer member D' is secured to the face 70 of the sash A by means of a screw E, which holds the frame D securely in position. The spindle d⁴ extends beyond the outer face of the member D³ of the holder-frame D, and upon this spindle is mounted the roller F, of 75 rubber or other compressible material, provided with a central bearing-sleeve f, which fits the spindle d⁴. The roller is retained in position upon the spindle by means of a flat metallic plate H, which is secured by screws 80 upon the edge of the sash A and is provided with a transverse slot h, leading from one edge thereof, into which slot the end of the spindle d⁴ extends. The roller is so arranged as to impinge against the inner side of the 85 strip C of the window-frame, and the amount of friction between this roller and the strip C may be regulated at will by a simple adjustment of the screw D⁴, which has the effect of moving the spindle and roller to or away from 90 the said strip C, as hereinbefore described and as will be clearly understood by inspection of Fig. 3.

I may use one or more holders upon one side of the sash or as many as desired or necessary upon both sides of the sash.

It will be seen that the holder not only serves to support the sash at any desired elevation, but it also serves to prevent rattling thereof and in cold weather to shut out wind, 100 snow, &c., which might otherwise find its way around the edge of the sash, between it and the frame of the window.

It will be seen that I provide a cheap, sim-

ple, and efficient sash-holder which is made adjustable to tighten or loosen the sash, as desired.

Having thus described my invention, what I claim, and desire to secure by Letters Patent of the United States, is—

1. In a sash-holder, the combination with a frame secured within a recess in the face of the sash-frame, a spindle mounted in said frame, and a screw passing through said spindle for adjusting the same, of a compressible roller mounted upon the said spindle and arranged to impinge against the retaining-strip of the window-frame, and means for retaining the said roller upon said spindle and for guiding the outer end of the said spindle, substantially as described.

2. In a sash-holder, the combination with a frame D secured in a recess in the edge of the sash-frame, said frame D having a slot d^3 through one end thereof, and the screw D^4 mounted to rotate in said frame, but not having its screw-threads engaging therewith; of the spindle d^4 having an enlarged base portion

D^5 provided with a screw-threaded opening 25 through which passes the said screw D^4 ; a compressible roller mounted upon the said spindle and arranged to impinge against the inner side of the retaining-strip of the window-frame, substantially as described.

3. In a sash-holder, the combination with a frame secured within a recess in the face of the sash-frame, a spindle mounted in said frame, and a screw passing through said spindle for adjusting the same, of a compressible 35 roller mounted upon the said spindle and arranged to impinge against the retaining-strip of the window-frame, and a plate secured upon the edge of the sash-frame provided with a transverse slot into which extends the said 40 spindle and which serves as a guide for the said spindle, substantially as described.

In testimony whereof I affix my signature in presence of two witnesses.

FRANK ALLEN.
